ABSTRACT: Twin carriages mounted for movement toward and from the edges of a traveling strip have guide rollers and cutting knives thereon adapted to engage the strip edges. The knives are carried on counterweighted cranks and serve to trim coating buildup in the form of "whiskers" from the strip as it is drawn along a predetermined path, after adjustment of the carriages to their proper positions. Suction means are disposed adjacent the knives and receive the coating material removed by the knives.

APPARATUS FOR REMOVING EXCESS COATING MATERIAL FROM STRIP EDGES

This invention relates to apparatus for removing the buildup of excessive coating material from the edges of traveling strip.

BACKGROUND OF THE INVENTION

In certain strip coating processes, e.g. the electrolytic process for the manufacture of tin plate, an excess of the coating metal accumulates on the strip edges in the form of whiskers and, when the coating is melted by heating, as one of the last steps in the process, the excess material forms beads along the strip edges which have a thickness substantially greater than that of the strip apart from the edges. This increased thickness causes difficulty in coiling the strip and has necessitated trimming off about a half inch of the strip width on both sides. This practice is obviously objectionable because of the added cost and the scrap produced.

I have invented apparatus for scraping the strip edges, after cooling and before remelting, to prevent the formation of these beads of excess coating metal.

SUMMARY OF THE INVENTION

In a preferred embodiment, I provide a beam extending across the path of the strip at a suitable point and mount for traversing movement along the beam a pair of carriages. Each carriage has a guide roller thereon, adapted to engage a strip edge, and a cutting knife, carried on a counterweighted crank, effective to remove excess coating material when brought against the strip edges. Each carriage has a fluid-pressure cylinder and piston for moving it to its normal effective position and retracting it therefrom. A pneumatic fragment-disposal system has inlets adjacent the knives whereby whiskers removed from the strip edges are conducted to a collection receptacle.

BRIEF DESCRIPTION OF THE DRAWINGS

A complete understanding of the invention may be obtained from the following detailed description and explanation which refer to the accompanying drawings illustrating the present preferred embodiment. In the drawings:

FIG. 1 is a plan view and FIG. 2 is an elevation, of a portion of an electrolytic tinning line between the coating section and the melting section;

FIG. 3 is an elevation, such as would be seen by looking from the right on FIG. 2;

FIG. 4 is an enlargement of a portion of FIG. 3;

FIG. 5 is a plan view corresponding to FIG. 4;

FIG. 6 is an elevation such as would be projected on the plane of line VI-VI of FIG. 4; and

FIG. 7 is a partial section taken along the line of plane VII-VII of FIG. 5.

DETAILED DESCRIPTION OF THE PREFERRED EMBODIMENT

Referring now in detail to the drawings and, for the present, particularly to FIGS. 1 and 2, strip S which has passed through the coating section of an electrolytic tinning line of known design, is delivered therefrom over an inspection roll 10 and downwardly past a guide roll 11, both journaled in bearings (10a and 11a, respectively) carried by spaced posts 12, between which the strip passes on its way to a conventional melting tower and further finishing operations, preparatory to coiling. Posts 12 stand on an inspection roll platform 13 fabricated from structural members and supported by suitable columns. A fabricated beam 13a rests on platform 13 and extends transversely of the path of strip S. As shown in FIGS. 2 and 3, the beam has a web 14 and flanges 15. Rails 16 extend along the outer surfaces of the flanges parallel to web 14.

A pair of spaced similar carriages 17 are adapted to travel along rails 16. Each carriage includes a base plate 18 having a post 19 upstanding thereon. Flanges 20 depending from opposite sides of the base plate have horizontal guide rollers 21

5 journaled thereon for engaging the upper and lower edges of rails 16 and vertical rollers 22 for engaging the outer lateral faces of the rails. A fluid-pressure cylinder and piston 23 resting on spaced angle bars 24 bridging flanges 15 of beam 13a, has its piston rod pivoted to an angle bracket 25 depending from the undersurface of base plate 18.

Post 19 has a cross bar 26, with spaced parallel slots 27 therein, bolted thereon. Angle brackets 28 are similarly secured to bar 26. A tubular shaft 29 is secured by clamps 29a to brackets 28 for angular adjustment. A pair of crank arms 30 mounted in spaced relation on shaft 29 by pins 31 extending radially thereof, supports an exhaust tube 32 by pins 33 similar to those shown at 31. The outer end of tube 32 has a hose 34 connected thereto which extends to a vacuum chamber 35. Shaft 29, arms 30 and tube 32 form a rectangular frame or yoke supported for angular adjustment about the axis of the shaft.

At the inner end, tube 32 has a pair of blocks 36, of suitable material, such as a phenol-formaldehyde resin, clamped thereto by screws 37 extending through holes in one and threaded into tapped holes in the other. The adjacent faces of the blocks are recessed to accommodate the end of tube 31 and further to provide a slot 38 and a tool socket 39 (see FIGS. 4, 5 and 7) communicating therewith. It will be observed from FIGS. 4 and 7 that socket 39 is also in direct communicating relation to the adjacent open end of tube 31. Blocks 36, as will shortly appear, form a tool-holding head at the inner end of tube 31.

30 A crank shaft 40 is journaled in the blocks 36 and has a crank arm 41 on which a counterweight 42 is slidably adjustable. A stop pin 42a limits rotation of shaft 40 under the torque exerted by the counterweight. A tool-holder block 43 extends downwardly from shaft 40 in socket 39 and has a cutting knife 44 secured thereto for engagement with the edge of strip S under the pressure resulting from the torque applied to shaft 40 by the counterweight. Excess material scraped from the strip edge by knife 44 is highly fragmented and is readily picked up in the airstream entering the end of tube 32.

45 Brackets 45 depending from blocks 36 support a shaft 46 bridging them and a roller 47 journaled on the shaft is adapted to engage the strip edge, as shown in FIG. 4, as the carriage is moved toward it. It will be understood that when the strip is traveling between posts 12 and over rolls 10 and 11, the carriages may be moved into cooperative relation with the strip edges (FIG. 3) by controlling the admission and exhaust of power fluid to and from cylinders 23. If lateral weave of the strip is substantial, known means may be provided to cause the carriages to maintain continuously the proper cooperative relation with the strip edges.

50 It will be apparent from the foregoing that the invention provides simple yet effective means for scraping excess coating material from strip edges and disposing of the material removed, pneumatically to a suitable point of collection.

55 Although I have disclosed herein the preferred embodiment of my invention, I intend to cover as well any change or modification therein which may be made without departing from the spirit and scope of the invention as set forth in the claims:

I claim:

1. An apparatus for removing excess coating material from an edge of a strip which travels along a predetermined path, said apparatus comprising a support extending in a direction parallel with the width of the strip and adjacent to the path thereof, a carriage mounted on said support and movable toward and away from the strip path, a yoke mounted on said carriage and including an exhaust tube extending close to the strip path, a head supported on said tube and having a slot adapted to receive the edge of the strip, a knife movably mounted on said head for engagement with the edge of the strip, means connected with said knife urging it towards the edge of the strip and said exhaust tube being positioned adjacent said knife whereby to receive the excess coating material removed by the knife.

2. An apparatus as defined in claim 1 further comprising a guide roll journaled on said head for engagement with the edge of the strip.

3. An apparatus as defined in claim 1 in which said yoke is angularly adjustable about an axis which is parallel with said support.

4. An apparatus as defined in claim 1 further comprising power means mounted on said support and connected with said carriage for moving the latter.

5. An apparatus as defined in claim 1 in which said head has a socket communicating with said slot, said knife is housed within said socket, the mounting for said knife includes the shaft journaled on said head, and the means urging said knife towards the edge of the strip includes a counterweight connected with said shaft.

6. An apparatus as defined in claim 5 in which said tube communicates directly with said socket.
